UNITED STATES PATENT OFFICE.

LUDWIG SCHEIBE, OF KRÖLPA, KR. ZIEGENRÜCK, GERMANY.

FOLDING CHAIR.

1,388,146.

Specification of Letters Patent. Patented Aug. 16, 1921.

Application filed April 9, 1921. Serial No. 460,024.

To all whom it may concern:

Be it known that LUDWIG SCHEIBE, cook, citizen of the German Republic, residing at Krölpa, Kr. Ziegenrück, Germany, have invented certain new and useful Improvements in or Relating to Folding Chairs, (for which I have filed applications in Germany, August 25, 1919; France, October 22, 1920; Belgium, October 27, 1920; Denmark, October 28, 1920; Netherlands, October 18, 1920; Swiss, October 28, 1920, and Great Britain, November 16, 1920,) of which the following is a specification.

Various kinds of folding or collapsible chairs are known. One type of collapsible chair is folded by moving the lateral supporting members toward one another, the said members being operatively connected to each other by scissor-like fittings or trellis-struts which are brought from the closed to the open position when the chair is folded. The seat is carried directly on supports secured to the upper ends of the trellis struts and displaced when the chair is being folded. The flexible seat sags and forms a pocket when the chair is in the folded position so that the thickness of the material becomes clumsily packed between its two supports and prevents the lateral members from being in contact. The folded chair therefore is not as compact as desired. The material of the seat is pinched and creased between the side members and is liable to get damaged when the chair is not opened for a long time. Another source of deterioration is that when the chair is in use the whole of the weight of the person seated thereon is borne by the flexible seat which is thus often torn. Finally when it is desired to fold the chair with care, the forming of the pocket must be watched and assisted, this requiring attention.

This invention relates to a folding chair of the kind in which, as already referred to, the side members are moved toward each other. The chair according to this invention is entirely free from the above-mentioned disadvantages in that one side of the seat is secured to a rod arranged on one of the lateral members. The seat then passes over the side struts secured to the upper ends of the trellis struts or scissor members and its other end is secured to a spring-controlled rod movably mounted on the opposite lateral member, and guided on the latter. The seat is thus always stretched and

slides under the action of the spring over the side struts fastened to the ends of the trellis struts when the chair is being folded or unfolded.

A construction of a folding arm-chair according to this invention is illustrated in the accompanying drawings in which—

Figure 1 is a front view partially in section.

Fig. 2 is a side elevation.

Fig. 3 is a section on the line A—B of Fig. 2 while the chair is being folded.

Fig. 4 is a similar section through the folded chair.

The two lateral members or frames *a* and *b* of the arm-chair comprise the arm rests *c* and *d* and the struts *e f g h*. The uprights of the frames *a* and *b* are provided with slots *i* and *k* located above the struts *g* and *h* and adapted to receive the pins *l* and *m* of the upper ends of the scissor or trellis struts *o* and *p*, the said ends being connected by rods *q* and *r* rounded off toward the outside. The seat *s* passes over the said rods. In the construction illustrated in Fig. 1 one of the ends of the seat is permanently clamped between the side strut *h* and a similar rod *r'*, the other end being secured to a sliding rod *t* located above the side strut *g* and provided with a handle *u* to which one end of a spring *v* may be fastened, the other end of said spring being secured to the lower strut *e*. Instead of being fastened to the handle *u* the spring may pass through a suitable hole in the upper strut *g* and be directly attached to the sliding rod *t*. The back of the arm-chair comprises uprights *x* and *y* carried by the arm rests *c* and *d* and supporting the back *w*.

Fig. 1 shows the arm-chair ready for use. The frames *a* and *b* move apart, the pins *l* and *m* sliding in the slots *i* and *k* until the rods *q* and *r* rest on the struts *g* and *h*, the sliding rod *t* being between the strut *g* and the rod *q*. The seat *s* with its downturned sides gripped is ready in this position to receive the occupant.

The arm-chair is folded by slightly raising the rods *q* and *r*, after which the lateral frames *a* and *b* are pushed toward one another (Fig. 3) so that the rod *r* slides under the seat *s* which at first lifts the sliding rod *t*. The spring *v* becomes stretched until it overcomes frictional resistance and pulls the sliding rod *t* down into the position illustrated in Fig. 4 so that the seat is never slack.

and does not sag in the folded position. If the spring *v* fails, the seat *s* may be stretched to its proper position by means of the handle *u*. The back *w* is folded in fanlike fashion.

5 As shown in Fig. 4, the chair in its folded position may still stand upright. In the position of use, the stays *z* prevent the chair from tipping over.

The arm-chair is unfolded by pulling the 10 arm rests *c* and *d* apart; the seat *s* comes automatically in position until the rod *t* bears against the rod *g*. The chair according to this invention is very light, is easily made and stored and is very stable even in 15 its most simple construction.

I claim:

1. A collapsible chair, the lateral members or frames of which are connected to one another by pivoted or trellis struts and in 20 which one side of the seat secured to one of the lateral frames passes over rods secured to the upper ends of the trellis struts, the other side of the said seat being secured to a spring-pulled sliding rod keeping the seat 25 stretched in any position of the chair.

2. A collapsible chair in accordance with claim 1, wherein one side of the seat is permanently clamped against a stationary strut the other side being secured to a sliding rod coming against a strut when in use.

3. A collapsible chair, comprising a pair of lateral frames, lazy-tongs connecting said frames and having pivoted connection at the lower ends of said frames and sliding connection at the upper ends thereof, cross rods 3 between the upper ends of said lazy-tongs, a flexible seat member fixedly secured at one end to one of said frames and yieldingly secured at the other end to the other of said frames, said seat member passing over both 4 of said cross rods, whereby the seat member will always be kept taut whether the chair is in open or closed position.

In testimony whereof I affix my signature in presence of two witnesses.

LUDWIG SCHEIBE.
